CUTTING TOOL

Oscar B. Burgeson, Bristol, Conn., assignor to The
Stanley Works, New Britain, Conn.

Filed May 11, 1971, Ser. No. 142,437

Term of patent 14 years

Int. Cl. D8—05

U.S. Cl. D8—58

FIG.4

FIG.1

FIG.2

FIG.3

FIG. 1 is a plan view of a cutting tool showing the new design;

FIG. 2 is an elevational view of one side thereof;

FIG. 3 is an elevational view of the side opposite that illustrated in FIG. 2;

FIG. 4 is an elevational view of the cutter end thereof;

FIG. 5 is a bottom view thereof;

FIG. 6 is a fragmentary plan view of the jaw end thereof with the handles and jaws in open position and drawn to an enlarged scale;

FIG. 7 is a sectional view along the line 7-7 of FIG. 6; and

FIG. 8 is a sectional view along the line 8-8 of FIG. 6.

I claim:

An ornamental design for a cutting tool, as shown.
